UNITED STATES PATENT OFFICE

111,540

DESIGN FOR A GAS RANGE ELECTRIC LAMP

Edward R. Guyer, Hinsdale, Ill., assignor to
Cribben and Sexton Company, Chicago, Ill., a
corporation of Illinois

Application August 18, 1937, Serial No. 71,182

Term of patent 3½ years

To all whom it may concern:

Be it known that I, Edward R. Guyer, a citizen of the United States residing at Hinsdale, county of Du Page and State of Illinois, have invented a new, original, and ornamental Design for a Gas Range Electric Lamp, of which the following is a specification, reference being had to the accompanying drawing forming a part

thereof, in which Figure 1 is a side elevational view of a gas range electric lamp showing my new design; and Fig. 2, a broken rear elevational view of the same.

I claim:

The ornamental design for a gas range electric lamp, as shown.

EDWARD R. GUYER.
